DUAL STEAM GENERATING APPARATUS

Sinai Lafleur, Detroit, Mich.

Application February 6, 1946, Serial No. 645,753

2 Claims. (Cl. 158—73)

1

My invention relates to a new and useful improvement in a dual steam generating apparatus adapted for use in combustion of a low grade oil in conjunction with which steam under pressure is utilized.

It is an object of the present invention to provide a mechanism of this class which will be simple in structure, economical of manufacture, durable, compact and highly efficient in use.

Another object of the invention is the provision in a mechanism of this class of a boiler associated with a generator element so arranged and constructed that the burner element will serve to generate steam in the boiler.

Another object of the invention is the provision in a mechanism of this class of a pair of auxiliary steam generating boilers, one of which is provided with an electric heating element whereby steam may be generated in the initial starting of the device and which later serves as a reservoir for steam generated by the burner itself in the auxiliary reservoir.

Another object of the invention is the provision in a mechanism of this type of a steam reservoir which will also serve as a hot water container for effecting a pre-heating of the oil or fuel which is being used.

Other objects will appear hereinafter.

It is recognized that various modifications and changes may be made in the detail of structure illustrated without departing from the invention itself and it is intended that such variations and modifications shall be encompassed within the scope of the claims which form a part hereof.

Forming a part of this specification are drawings in which:

Fig. 1 is a side elevational view of the invention;

Fig. 2 is a sectional view taken on line 2—2 of Fig. 1;

Fig. 3 is a sectional view taken on line 3—3 of Fig. 2;

Fig. 4 is a fragmentary, enlarged, sectional view taken on line 4—4 of Fig. 2.

In the drawings, I have illustrated the invention as embodying a container 17 leading into which are spaced apart pipes 18 and 19, which serve to connect the container 17 with the boiler or steam generator 20 so that water may circulate between the containers 17 and 20. A water supply pipe 21 is connected to a suitable source of water supply and serves to conduct water into the container 17. A float operated valve 22 operated by the float ball 23 serves to control the flow of water into the container 17. A pipe 24

serves to communicate the containers 17 and 20 adjacent their upper ends so that steam generated in the boiler or generator 20 may pass into the upper side of the container 17. This container 17 is provided with a suitable safety valve 25 connected with the interior of the container 17 by the piping 26. A pressure gauge 27 is mounted on the container 17 to indicate the pressure therein and the outlet pipe 28 communicates with the container 17 and serves to conduct steam therefrom to the valve housing 29.

Positioned in the container 17 is an electric heating element 30 having a base 31 through which projects a terminal 32 whereby this heating element may be suitably connected to a source of electrical energy.

Passing through the reservoir or container 17 is an oil or fuel conducting pipe 33 which connects to a suitable source of supply and serves to conduct the oil to the metering valve 34 which communicates through the solenoid operated valve 35, electrically connected by the wires 36 to a suitable source of electrical energy, to the delivery pipe 37 which attaches to a nipple 38. This nipple is mounted on a nozzle head 39 and communicates through passage 40 with chamber 41. Nipple 43 communicates with the chamber 41 through passage 42 and is connected to the steam line 44. The steam line has a hand operated valve 45 and a solenoid operated valve 46 therein for controlling the steam supply to the nozzle head 39. The valve 46 is controlled through wires 47. The nozzle head has an end wall 50 for the chamber 41, a passage 51 through same and a screen hood over and spaced from the end of wall 50. Steam through passage 42 draws in oil through passage 40 and ejects same through passage 51, there being an atomization in the process. The screen tends to further break of the oil and the burning takes place just outside of screen 52.

In operation, the water delivery pipe 21 will serve to deliver into the container 17 the amount of water required to operate the float valve and close it so that a constant supply of water in the container 17 is provided. This, of course, will be indicated on the water glass 49. This water is permitted to flow into the container or steam generator 20 through the pipes 18 and 19. In order to start the mechanism, the electrical heating element 30 is connected to a source of electric energy and this heating element is used until steam is generated in the container 17 so that there shall be sufficient steam to start the burner operating. As soon as the burner is operated a sufficient time to generate steam in the gener-

ator 20, the heating element 30 is disconnected. The water in the container 17 and in the generator 20 will thus be maintained at the boiling point at all times and it will be noted that the oil delivery pipe 33 being submerged in this boiling water will serve as a means for pre-heating this fuel oil so that a low grade of fuel oil may be used.

The volume of flow of fuel oil may be metered or controlled by the valve 34. When the mechanism is operating, the solenoid valves 35 and 46 will be controlled by a thermostat in a room to be heated. These solenoid valves are constructed alike so that a description of one will suffice for both. When the thermostat in the room is such as to close the valves 35 and 46, the burner would go out were there no provision for a continued supply of fuel and steam to the burner. This is accomplished by a bypass through the solenoid valve.

The mechanism is of sufficiently compact and small design that it may be transported from place to place so that there is thus provided a portable burning mechanism associated with a portable boiler. Thus, I have provided a heating mechanism which will lend itself to many uses where a portable construction is required. The design is one which has proven itself most efficient in use and quite economical to manufacture.

What I claim as new is:

1. A device of the class described comprising: a water container for containing water at a predetermined level; a steam generator for containing water; a pair of pipes, one positioned above the other and connecting said container and said generator with each other below the water level; a pipe connecting said container and said generator with each other above the water level for conducting steam from said generator into said container; a fuel nozzle; a conduit for conducting fuel oil to said nozzle, said conduit passing through said container below the liquid level therein; an electric heating element in said container for heating the liquid and generating steam therein; and a conduit for conducting steam from said container to said nozzle, the relative positions of said nozzle and said generator being such that fuel issuing from said nozzle and burning serves to generate steam in said generator.

30

40

zle, the relative positions of said nozzle and said generator being such that fuel issuing from said nozzle and burning serves to generate steam in said generator.

2. In a device of the class described, a liquid container for containing water at a predetermined level; a steam generator positioned adjacent said container in spaced relation thereto; a conduit for connecting said container and said generator together below the level of water in said container for maintaining the same level of water in said generator and in said container; a conduit connecting said generator and said container together above the water level for conducting steam from such generator into said container; a fuel nozzle; a conduit for conducting fuel oil to said nozzle, said conduit passing through said container below the liquid level therein; a conduit for conducting steam from said container to said nozzle, the relative positions of said nozzle and said generator being such that fuel issuing from said nozzle and burning serves to generate steam in said generator.
